(57) **CLAIM**

The ornamental design for a blower attachment, as shown and described.

DESCRIPTION

FIG. 1 is a perspective view of the blower attachment of my new design.

FIG. 2 is a front elevational view thereof.

FIG. 3 is a top plan view thereof.

FIG. 4 is a back side elevational view thereof.

FIG. 5 is a bottom plan view thereof.

FIG. 6 is a left side view thereof.

FIG. 7 is a right side view thereof.

FIG. 8 is a cross sectional view of the blower attachment through line 8-8 of FIG. 3; and,

FIG. 9 is a view with parts broken away of the blower attachment along line 9-9 of FIG. 3.

The broken lines shown in the drawings illustrate portions of the blower attachment that forms no part of claimed design.
